A. E. SHODIN

ROOF TRUSS

Filed May 18, 1923

Inventor
ALBIN E. SHODIN
or Hazard Miller
att

UNITED STATES PATENT OFFICE.

ALBIN E. SHODIN, OF LOS ANGELES, CALIFORNIA.

ROOF TRUSS.

Application filed May 18, 1923. Serial No. 639,813.

To all whom it may concern:

Be it known that I, ALBIN E. SHODIN, a citizen of the United States, residing at Los Angeles, in the county of Los Angeles and 5 State of California, have invented new and useful Improvements in Roof Trusses, of which the following is a specification.

This invention relates to architectural elements, and more particularly to roof 10 trusses.

It is an object of the present invention to provide an improved roof truss of wooden elements. An object is to provide a truss in which the stanchions spring in perpendicular position from abutting portions at their 15 ends; in other words, it is an object to provide, in a truss, stanchions with end faces at right angles to their length so as to secure a joint end connection free from tendency 20 to slip under load, as is the case when either end or both of the ends of the stanchions are cut obliquely to the length of the stanchion. Another object is to provide a 25 hollow stanchion eliminating grooving of the stanchion elements, and yet provide for a ventilating rod chamber.

Other objects and advantages will be made manifest in the following specification of an embodiment of the invention illustrated in the accompanying drawings, 30 wherein

Figure 1 is a side elevation, parts being in section, of the improved truss.

Fig. 2 is a top plan of the truss.

Fig. 3 is a section on line 3—3 of Figure 1.

Fig. 4 is a cross section on line 4—4 of Figure 1 through a stanchion.

Fig. 5 is a section on line 5—5 of Figure 1.

The truss of my present invention may be 40 regarded as having a hollow springer or arch component which is built up of upper and lower sets 2 and 3 of planks. Each set may consist of any suitable number of planks; in the present embodiment, the upper set includes two layers of planks 2^a, while the lower set includes two layers of planks 3^a. It is understood that each layer of the truss will consist of one or more planks, according to the length of the arch.

50 The upper and lower sets of arch planks are spaced by spacer blocks 4, transversely arranged, and at the center of the arch, where the space 5 between the plank sets is the greatest, there will be placed a spacer 55 block of greatest thickness, and the space 5

is shown as gradually decreasing in height towards the ends of the arch and the transverse spacing blocks 4 will be of a thickness corresponding to the height of the space 5, according to their position in the arch or 60 bow. The sets of planks are firmly secured to each other and clamped upon the intermediate spacing blocks 4 as by means of clamp bolts 6 passing therethrough.

It is obvious that the arch or bow may 65 be of any suitable or required dimensions, and that the dimensions of the planks and their arch forming elements will be varied correspondingly to obtain the desired spring.

The ends of the arch element are sprung 70 down toward the ends of a transverse or chord element 10, which is preferably built up of planks 10^a set face to face against each other and being disposed with their longitudinal, broad faces in vertical position, as 75 clearly shown in Figure 5. There is thus formed a laminated beam or chord member 10.

The arch or bow element has its ends supported against thrust straps or stirrups 11, 80 having side or cheek plates 11^a, extending down the sides of the chord 10 and secured thereto as by means of bolts 12 passing through the chord from side to side. Interposed between the lower end portions of the 85 arch or bow member are wedges or blocks 13 having top faces conforming to the contiguous lower end faces of the arch and having bottom faces that are mortised into seats 14; cut in the top of the chord 10. 90 Means are provided for holding the ends of the arch on top of the chord 10, and such means are shown as including transverse cross plates, or bars 15, arranged on the top and bottom of each end of the arch member 95 and chord member; these clamping bars projecting sufficiently beyond the sides to provide for attachment to tie-bolts 16, which extend along the sides of the truss parts and cross the cheeks of the stirrups.

100 A feature of the invention is the provision of stanchions forming braces between the bow or arch and the chord of the truss, and such stanchions are here shown as being of the built up type, including parallel 105 plank sides 18 between which are placed perpendicular spacing strips 19, which therefore form a built up construction forming an interior chamber 20 for the reception of a tie or clamp bolt rod 21, the ends of which 110

pass through the chord 10 and the bow structure 2-3. This hollow form of stanchion provides a chamber in which the bolt rod 21 is disposed, and this chamber is provided with ventilating apertures 20^a for the circulation of air.

To obtain thoroughly rigid construction of truss, I prefer that the ends of the stanchion be cut perpendicular to the length of 10 the stanchion and this, therefore, enables the firm abutting of the stanchion against contiguous faces as of the arch or bow member and on parts on the chord member. This avoids an oblique abutting joint between the 15 stanchion ends and the faces immediately engaged thereby, and overcomes possibility of slippage of the ends of the stanchions on their abutments.

The upper ends of the several stanchions 20 are shown as bearing directly against the lower, contiguous face of the arch or bow structure, and the lower ends of the stanchions bear against intermediate buttress members or blocks 23, the meeting faces of 25 the stanchions and the blocks 23 being at right angles to the length of the stanchions. The buttress blocks are shown as countersunk in recesses or seats 24 provided therefor in the top faces of the chord 10.

30 From the above it will be seen that I have provided a truss structure including an arch member formed of spaced, laminated plank sets, and these sets are reinforced by filler pieces disposed in the spaces between the sets. 35 Further, I have provided a timber truss including bracing stanchions between the bow and the chord, which have perpendicular end

faces engaging the contiguous abutting portions of or on the truss element.

Further embodiments, modifications and 40 variations may be resorted to within the principle of the invention.

What is claimed is:

In a timber truss, a bow-shaped top member of laminated structure in which certain 45 of the laminae are vertically spaced between the ends, spacing blocks between the spaced laminae and secured thereto, a bottom chord forming a tie between the extremities of the top member, said chord being built of tim- 50 bers set face to face, thrust straps secured to end portions of said chords, the sides of each of said straps being secured to opposite sides of said chord and at an angle thereto, the transverse portions of said straps being 55 adapted to support the ends of said bow- shaped member, wedges interposed between the end portions of said bow-shaped member and said chord and set into mortises in said chord, plates on the upper face of said bow- 60 shaped member at end portions of the latter, plates under said chord at end portions thereof connected to the first mentioned plates, buttress members seated in mortises in said chord, radially disposed stanchions 65 extending between said bow-shaped member and said buttresses, said stanchions being of the built-up type and being hollow, and tie 70 bolts extending through said stanchions and through said bow-shaped member and said chord transversely.

In testimony whereof I have signed my name to this specification.

ALBIN E. SHODIN.
